SHAPER ATTACHMENT FOR A LATHE

Clifford L. Mayers, Omaha, Nebr.

Application October 1, 1938, Serial No. 232,870

7 Claims. (Cl. 29—30)

This invention relates to a shaper and more particularly to an attachment in the form of a shaper which may be combined with and mounted on a lathe.

- 5 An object of this invention is to provide an attachment in the form of a shaper which may be detachably mounted on a conventional lathe construction without changing the present parts of the lathe structure.
- 10 A further object of this invention is to provide an attachment in the form of a shaper which may be mounted on a conventional lathe and which includes means for automatically feeding the work support during the operation of the
- 15 attachment.

A still further object of this invention is to provide a novel means for reciprocating the ram forming part of the attachment, the reciprocation of the ram being effected by means of a device adapted to be applied to the spindle of the lathe and including means whereby the length of the stroke of the ram may be varied at will.

A still further object of this invention is to provide in an attachment of this kind means connected to the ram reciprocating device mounted on the spindle whereby the work supporting carriage may be moved forwardly at each stroke of the ram.

A further object of this invention is to provide in a structure of this kind means whereby the position of the ram relative to the work support may be varied without changing the length of the stroke of the ram.

To the above objects and others which may hereinafter appear, the invention consists of the novel construction, combination and arrangement of parts as will be more specifically referred to and as illustrated in the accompanying drawings, wherein is shown an embodiment of the invention, but it is to be understood that changes, variations and modifications may be resorted to which fall within the scope of the invention as claimed.

In the drawings:

Figure 1 is a detail side elevation of an attachment constructed according to this invention,

Figure 2 is a detail side elevation of the attachment looking at the attachment from the side opposite from that side shown in Figure 1 and showing the device applied to a lathe,

Figure 3 is a detail front elevation of the device mounted on a lathe,

Figure 4 is a detail bottom plan of the attachment,

Figure 5 is a fragmentary top plan of the ram adjusting mechanism,

Figure 6 is a sectional view taken on the line 6—6 of Figure 5,

Figure 7 is a sectional view partly in elevation taken on the line 7—7 of Figure 4,

Figure 8 is an enlarged sectional view partly in elevation taken on the line 8—8 of Figure 4,

Figure 9 is a sectional view partly in elevation taken on the line 9—9 of Figure 4,

Figure 10 is an enlarged fragmentary sectional view of the ratchet feeding mechanism,

Figure 11 is a fragmentary sectional view of the connecting link between the operating plate mounted on the lathe spindle and the ram, and

Figure 12 is an enlarged fragmentary sectional view showing the feed operating means connected to the operating plate mounted on the spindle.

Referring to the drawings, and first to Figures 1 to 4 inclusive, the numeral 15 designates generally the head stock of a lathe which is mounted on a bed 16. The head stock 15 includes a pulley structure 17 of stepped construction by means of which the speed of rotation of the spindle 18 may be varied. The pulley or sheave 17 is adapted to be operated by a power means (not shown) and if desired the spindle 18 may be directly coupled with a power means. The lathe structure including the head stock 15 and the bed 16 is conventional lathe structure and is here shown as only one type of lathe structure with which the hereinafter described attachment may be combined.

In order to provide a means whereby the lathe structure may be used for operation of a shaper I have provided a frame structure generally designated as 19 which is of substantially right angular configuration in side elevation and which as shown in Figure 2 is adapted to rest on and be secured to the bed 16 of the lathe. The frame structure 19 includes a horizontally disposed guide member 20 provided with a pair of downwardly extending flanges or legs 21 which are adapted to rest on the upper side of the bed 16 at a point closely adjacent the spindle 18 of the head stock 15. A ram 22 which is provided on opposite sides thereof with slide members 23 is adapted to slidably engage the guide member 20 and an elongated guide bar 24 is secured as by bolts 25 to the guide member 20 so as to slidably engage the slide members 23 and hold these members 23 against vibration during the reciprocation of the ram 22.

A ram operating plate 26 provided with a hub portion 27 is adapted to be threaded onto the

forward end of the spindle 18 and this plate 26 is of a diameter sufficient to provide the necessary reciprocation of the ram 22. The operating plate 26 is provided on one face thereof with a 5 pair of flanged guide members 28 which are secured to the adjacent face of the plate 26 by means of bolts 29. A bolt 30 is adapted to engage between the confronting faces of the Z-shaped guide members 28 and is provided with an enlarged head 31 engaging in the channel 32 at the inner portion of the guide members 28. An 10 operating link 33 has one end thereof rockably mounted on the bolt 30 being detachably secured by means of a threaded nut 34. The opposite end 15 of the link 33 is rockably mounted on a horizontally disposed stud 35 carried by an adjustable block 36. The block 36 is mounted on the rear portion of the ram 22 being mounted on an 20 upper standing flange 37 of looped construction. The flange 37 provides an elongated slot 38 within 25 which a portion of the block 36 engages with another portion of the block 36 engaging on the upper side of the looped flange 37. A bolt 39 is extended through the block 36 being provided with a handle 40 at its upper end and the lower 30 end of the bolt 39 is threaded through a bar 41 engaging across the slot 38 interiorly of the ram 22 which is preferably made of hollow construction. The bolt 39 is adjustable along the length 35 of the guide member 28 so that the position of the bolt 39 relative to the axial center of the plate 26 will determine the length of the stroke of the ram 22. The position of the ram 22 relative to the 40 guide member 20 and to the work support, hereinafter described, may be determined by the adjustment of the block 36 relative to the slot 38 in the rear portion of the ram 22.

The frame 19 includes a vertically disposed frame part 42 which extends downwardly of the 45 horizontal guide member 20 and is positioned on the front side of the bed 16 as shown in Figure 2. The vertical frame member 42 is provided with a pair of guide members 43 on opposite sides thereof which are engaged by a carriage supporting member 44. The carriage supporting member 44 is secured to the guide members 43 in adjusted position by means of a clamping plate 45 which engages the inner side of a guide member 43 and is tightened by means of bolts 46. The 50 carriage supporting member 44 is provided at its upper and lower sides with guide members 47 and a work supporting carriage generally designated as 48 is slidably carried by the guide members 47. The carriage 48 includes a forwardly 55 projecting body 49 and a pair of slide members 50 engaging about the guide members 47 so that the carriage 48 may have a horizontal sliding movement along the length of the guide members 47. A work supporting table 51 is secured as by bolts 52 to the upper side of the carriage 48 and includes a stationary clamping block 53 and a movable clamping block 54 which is operated by means of a pair of clamping screws 55. The 60 article which is being worked upon is clamped between the two blocks 53 and 54. The work supporting table 51 is of conventional construction and includes means whereby the angular position of the table 51 may be adjusted about a rotatable base structure 56. The base structure 56 is adapted to be secured in its adjusted position by means of a set screw or locking member 57.

The ram 22 is provided at the forward end thereof with a head 58 on which is mounted an 70 adjustable base member 59 carrying a tool car-

riage 60. The tool carriage 60 is adjusted vertically by means of a feed screw 61 operated by means of a handle 62. The base part 59 may be rotated and locked in adjusted position by means of a pair of locking bolts 63 which engage through the base 59 and extend into the head 58 of the ram 22.

The carriage 60 includes a box or a pair of flanges 64 which are provided with a base part 65 having an arcuate slot 66. The center of the box member 64 is mounted on a pivotal member (not shown) and a bolt 67 extends through the arcuate slot 66 into the body part of the carriage 60 so that the box 64 may be rotated through the arc 66 in order to swing the tool post 68 to the 15 desired angle. The tool post 68 is of conventional construction and is mounted at its inner end on a base member 69 carried by a pair of pivotal members 70 engaging through the flanges 64. In this manner the tool carried by the post 20 68 may loosely slide over the work mounted on the work table during the back stroke of the ram 22.

The frame member 19 is detachably secured to the bed 16 of the lathe by means of a downwardly extending bar or bolt 71 which extends between the two guide portions forming the bed 16 and extends through a clamping bar 72. A nut 73 is threaded onto the lower end of the bolt or bar 71 and provides a means whereby the frame 19 30 may be detachably secured on the bed 16.

The carriage 48 is progressively moved along the carriage supporting member 44 by means of a feeding screw 74 which is threaded through a nut (not shown) carried by the rear portion of the carriage 48. The feeding screw 74 has a gear 75 secured adjacent one end thereof and a knurled knob or wheel 76 is also secured to the threaded shaft or screw 74 so that if desired, the screw 74 may be manually rotated in order to either manually feed the carriage 48 or to initially set this carriage at a predetermined position for the cutting of the article by the tool mounted on the tool post 68. The countershaft 77 is rotatably carried by the supporting member 44 and a gear 78 is fixed 40 to the countershaft 77. An intermediate gear 79 is mounted on a shaft 80 carried by the supporting member 44 and this intermediate gear 79 meshes with the gear 78 and gear 75. A ratchet member 81 is also fixed to the countershaft 77 at one side of the gear 78. A spring-pressed dog or pawl 82 is mounted in a housing 83 carried by a rock member 84. The rock member 84 is rockably mounted on the shaft 77 and the housing or cylinder 83 is radially disposed with respect to the axis of the 55 shaft 77. A spring 85 engages about the shank 86 integral with the pawl member 82 and constantly urges the pawl member 82 into engagement with the teeth of the ratchet 81. A knob 87 is secured to the upper or outer end of the stem 86 60 and a laterally extending pin 88 is secured to the stem 86 and when the pawl 82 is in operative position the pin 88 is adapted to slidably engage in a slot 89 provided in the outer end portion of the housing 83. The pawl member 82 may be moved 65 to a disengaged or inoperative position by pulling the knob 87 and the pawl 82 upwardly and then turning the knob 87 and the stem 86 so that the pin 88 will be disposed on the outer end of the housing 83 and at one side of the slot 89. The 70 rock member 84 is provided with an arm 90 in which a pin 91 is rockably mounted. The pin 91 has a rod 92 extending right angularly therethrough and the rod 92 is adjusted relative to the pin 91 by means of a threaded bolt 93. The upper 75

end of the rod 92 is rockably mounted on a pin 94 which extends through a slot 95 in an arm 96. A nut 97 is threaded onto the pin 94 and provides a means whereby the rocking movement of the rod 92 may be regulated so as to provide the desired feeding of the carriage 48. The arm 96 is secured to a shaft 98 journaled through the base members 21 and a lever 99 is fixed to the shaft 98 between the legs or flanges 21. A second shaft 100 is journaled through the legs or flanges 21 in spaced relation to the shaft 98 and a lever 101 is secured to the second shaft 100 and is connected to the first lever 99 by means of a link 102. An operating lever 103 is secured to one end of the shaft 100 and this lever 103 has a roller 104 carried by a pin 105 at the free end of the lever 103. The roller 104 is positioned in a cam track 106 provided on the face of the plate 26 opposite from the guide member 28. The cam track 106 is of such a configuration that during the forward or operating stroke of the ram 22, the feeding mechanism hereinbefore described will be inoperative, but when the ram 22 moves rearwardly on the inoperative or back stroke, the feeding mechanism will be effective so as to rock the lever 103 and through this lever 103 rotate the feeding screw 74.

In the use and operation of this device, the tool carriage provided on the conventional lathe is moved to one side of the head stock 15 and the frame structure 13 is then mounted on the bed 16 as shown in Figure 2. The bolt or bar 71 extends between the two track portions forming the bed 16 and the frame 19 is tightly clamped by means of the bar 72 and the nut 73. The operating plate 26 is threaded onto the spindle 18 of the lathe and in this manner the rotary movement of the spindle 18 is translated by means of the plate 26 and the link 33 to reciprocatory movement. The desired tool is inserted in the tool post 68 and the work is clamped on the work table 51 by means of the clamping members 53 and 54. The carriage supporting member 48 may be initially adjusted to the desired vertical position so that the tool may readily engage the desired portion of the work. After this has been done, the tool carriage may be vertically adjusted or angularly adjusted in order that the tool may contact with the work. Rotation of the plate 26 will cause the ram 22 to reciprocate back and forth, and simultaneous with the back stroke of the ram 22, the feeding screw 74 will be rotated progressively by means of the rock member 84 which is rocked under the vertical movement of the rod 92. The rod 92 is rocked under the action of the levers 96, 99, 101 and the linkage 102 and 103.

An attachment constructed according to this invention may be quickly mounted upon or removed from a conventional lathe structure, it only being necessary that the hub portion 27 of the operating plate 26 be provided with the necessary threaded opening to threadably engage the end of the lathe spindle 18. A device constructed according to this invention will make it possible for a relatively small shop to have the use of a shaper at a relatively small cost and this shaper may be set up without requiring an additional amount of space in the shop as the entire attachment is adapted to be mounted on the present structure of the lathe.

The pin 88 extends on opposite sides of the shank or stem 86 of the pawl 82 so that if desired the pawl 82 may readily be reversed in order to effect reverse feeding of the carriage 48. The opening 89 extends diametrically across the hous-

ing 83 so that the pin 88 may be swung in an arc of 180° to reverse the pawl 82.

What I claim is:

1. An attachment for use with a lathe having a bed and a driven spindle, said attachment comprising the combination of a supporting structure for securing on said bed and formed with a depending portion, a reciprocatory shaper mechanism mounted on the top of and slidably connected to said structure, a revolvable disc like driver adapted to be connected to and operated from said spindle, said driver being provided respectively on one of the faces with means disposed diametrically thereof to provide a combined connection and guide groove forming element and on its other face with a cam track, a lower structure secured to and disposed in lateral relation with respect to said depending portion, said lower structure including a shiftable, slidably mounted work feed, an operative driving connection between said element and mechanism for reciprocating the latter, a ratchet mechanism carried by said structures for intermittently shifting said work feed, and means travelling on and leading from said cam track to said ratchet mechanism for operating the latter intermittently.

2. An attachment for use with a lathe having a bed and a driven spindle, said attachment comprising the combination of a supporting structure for securing on said bed and formed with a depending portion, a reciprocatory shaper mechanism mounted on the top of and slidably connected to said structure, a revolvable disc like driver adapted to be connected to and operated from said spindle, said driver being provided respectively on one of the faces with means disposed diametrically thereof to provide a combined connection and guide groove forming element and on its other face with a cam track, a lower structure secured to and disposed in lateral relation with respect to said depending portion, said lower structure including a shiftable, slidably mounted work feed, an operative driving connection between said element and mechanism for reciprocating the latter, a ratchet mechanism carried by said structures for intermittently shifting said work feed, and means travelling on and leading from said cam track to said ratchet mechanism for operating the latter intermittently, the said ratchet mechanism including selectively positioning means for controlling the direction of the feeding of the work to be acted upon.

3. An attachment for use with a lathe having a bed and a driven spindle, said attachment comprising the combination of a supporting structure for securing on said bed and formed with a depending portion, a reciprocatory shaper mechanism mounted on the top of and slidably connected to said structure, a revolvable disc like driver adapted to be connected to and operated from said spindle, said driver being provided on one of the faces with means disposed diametrically thereof to provide a combined connection and guide groove forming element and on its other face with a cam track, a lower structure secured to and disposed in lateral relation with respect to said depending portion, said lower structure including a shiftable, slidably mounted work feed, an operative driving connection between said element and mechanism for reciprocating the latter, a ratchet mechanism carried by said structures for intermittently shifting said work feed, means travelling on and leading from said

- cam track to said ratchet mechanism for operating the latter intermittently, the said operative driving connection including adjustable means for controlling the length of the stroke of said shaper mechanism, and said ratchet mechanism including adjustable means for controlling the extent of the intermittent shift of the work feeder.
4. In an attachment for use with a lathe having a bed and a driven spindle, said attachment including a supporting structure for securing on said bed, an adjustable reciprocatory shaper structure mounted on and slidably connected to said structure, a revolvable driver adapted to be connected to and operated from said spindle, said driver being provided on one face thereof with means to provide a combined connection and guide groove forming element, a link, means for pivotally supporting one end of the link and for slidably connecting said end to said element whereby the link is shifted from the driver, said shaper mechanism including an upstanding flange of loop-like form, an adjustable block mounted on and having a part extending into said flange, a stud on said block, the other end of said link being pivotally mounted on and secured to the stud whereby the link is attached to said block, and means for securing the block in its adjusted and non-adjusted position to couple the link to said mechanism.
5. In an attachment for use in a lathe having a bed and a driver spindle, said attachment including a shaper mechanism supporting structure formed with a depending portion, a lower structure secured to and disposed in lateral relation with respect to said depending portion, said lower structure including a shiftable slidable mounted work feed, a revolvable driver for connection to and operated from said spindle, said driver being formed on one face thereof with a cam track, means for shifting the work feed, a ratchet mechanism secured to said structures for intermittently operating said shifting means, and a link travelling in and leading from said cam track to said ratchet mechanism for intermittently operating the latter on the operation of the driver, said ratchet mechanism including means for controlling the extent of the intermittent operation thereof.
6. In an attachment for use in a lathe having a bed and a driver spindle, said attachment including a shaper mechanism supporting structure formed with a depending portion, a lower structure secured to and disposed in lateral relation with respect to said depending portion, said lower structure including a shiftable slidable mounted work feed, a revolvable driver for connection to and operated from said spindle, said driver being formed on one face thereof with a cam track, means for shifting the work feed, a ratchet mechanism secured to said structures for intermittently operating said shifting means, and a link travelling in and leading from said cam track to said ratchet mechanism for intermittently operating the latter on the operation of the driver, said ratchet mechanism including means for controlling the extent of the intermittent operation thereof.
7. In an attachment for use in a lathe having a bed and a driver spindle, said attachment including a shaper mechanism supporting structure formed with a depending portion, a lower structure secured to and disposed in lateral relation with respect to said depending portion, said lower structure including a shiftable slidable mounted work feed, a revolvable driver for connection to and operated from said spindle, said driver being formed on one face thereof with a cam track, means for shifting the work feed, a ratchet mechanism secured to said structures for intermittently operating said shifting means, and a link travelling in and leading from said cam track to said ratchet mechanism for intermittently operating the latter on the operation of the driver, said ratchet mechanism including means for selectively controlling the direction of the shift of the said work feed.

CLIFFORD L. MAYERS.
